UNITED STATES PATENT OFFICE.

OLOF EWART ANDERSON, JR., OF ASTORIA, OREGON.

POWDER-CONTAINER.

1,294,596.

Specification of Letters Patent. Patented Feb. 18, 1919.

Application filed April 17, 1918. Serial No. 229,195.

To all whom it may concern:

Be it known that I, OLOF EWART ANDERSON, Jr., a citizen of the United States, and a resident of Astoria, in the county of Clatsop and State of Oregon, have made certain new and useful Improvements in Powder-Containers, of which the following is a specification.

My present invention relates generally to powder containers, and more particularly to a dispensing container for various uses, my object being the provision of a container including means whereby the powder will be sifted as dispensed, and whereby the dispensing operation may be accomplished readily and quickly.

A further object of my invention is to provide a simple, inexpensive mechanism which may be mounted in connection with a wall bracket and the like at any convenient point, and a proper supply of powder ascertained and readily maintained at all times.

In the accompanying drawing illustrating my present invention:

Figure 1 is a view partly in side elevation and partly in vertical section through my improvements;

Fig. 2 is a vertical transverse section taken centrally through the lower portion of the container and its dispensing holder;

Fig. 3 is a longitudinal section through the actuating stem and its barrel;

Fig. 4 is a detailed perspective view of the agitating frame with its cut off;

Fig. 5 is a bottom plan view of a portion of the holder, and,

Figs. 6 and 7 are detailed sections through the dispensing stem and its barrel taken respectively on lines 6-6 and 7-7 of Fig. 1.

Referring now to these figures, my invention proposes the use of a transparent container 10 for powder and like material having its upper and lower ends reduced, the latter being threaded as at 11, and the former having a surrounding band 12 supporting a lid or cover 13 by means of which the supply of powder within the container may be readily replenished from time to time as needed, the transparent wall of the container permitting the user to view the supply and thus readily determine when it should be replenished. The container 10 being thus open at its upper and lower ends the threads 11 at its lower end adapt the same to be screwed within the upper internally threaded

opening of a holder generally seen at 14, having an enlarged hollow body 15, and a rearwardly projecting stem 16.

The body 15, in the upper portion of which the container 10 is mounted, thus communicates with the interior of the said container and is provided at its lower portion with a series of openings 17 forming a sieve and permitting of discharge of the sifted powder through an apertured lower cap 18.

The stem 16 has an axial bore which receives the inner end of a barrel 19, the forward portion of which projects forwardly through the hollow body 15, and through a bearing aperture in the front wall thereof, which bearing aperture is surrounded by a bracket 20 having an inturned lip 21 extending within the longitudinal slot 22 of a threaded dispensing stem 23 having a handle 24 at its forward end.

The barrel 19 is internally threaded as seen at 25, particularly in Fig. 3, the threads of which are engaged by the external threads 26 of the stem 23, said threads 25 and 26 being spirally arranged so that when the handle 24 is grasped and the stem 23 thrust rearwardly within the barrel, the latter will be forced to rotate by virtue of the fact that the stem 23 is held against rotation by the lip 21 of the bracket 20.

Mounted upon the barrel 19 within the hollow of the body 15 and rotatable therewith, is a frame consisting of end spiders 27 supporting apertured stirring arms 28, disposed parallel to the axis of the barrel 19 in spaced relation thereto and also supporting a curved cover plate 29 which normally overlies the series of discharge openings 17, as seen in Fig. 2 so as to prevent outflow.

At the inner end of the barrel 19 is a plug 30 having a rod 31 projecting axially through the barrel and partly through the hollow stem 23, this rod 31 forming a support for a coil spring 32 disposed around the same between the plug 30 and the forward end of the stem 23, so as to normally hold the same in its forward or outer position at which time the frame within the hollow body 15 stands in the position shown in Fig. 2.

The stem 16 may have a threaded counterbore adjacent its rear end to adapt the same to connection upon a threaded stud and the like 33, projecting for instance from a wall or like bracket 34 so that the container 10

as well as the dispensing parts in connection therewith may be supported at any point convenient to the operator.

It is obvious that when a supply of powder is desired, the operator places one hand or a receptacle beneath a discharge opening of the lower cap 18, and with his other hand presses inward against the handle 24 thrusting the stem 23 longitudinally within the barrel 19 in a rearward direction and causing rotation of the latter, so that the stirring frame will be rotated. Upon initial rotation of this stirring frame the cover plate 29 leaves the normal position shown in Fig. 2, so that the several discharge openings 17 are uncovered and during rotation the arms 28 successively act to agitate the powder and cause the same to fall through the several discharge openings, foreign matter, lumps, and the like being retained within the hollow body 15.

I claim:

1. A dispensing device including a hollow body having a projecting stem and provided with a hollow rotatable barrel internally threaded and mounted through the body, and a portion of said stem, said hollow body having a sieve like lower discharge portion and a rotatable stirring frame therein connected to the barrel, a stem movable in the barrel and threaded to engage the threads thereof, said stem having a longitudinal slot, a bracket secured to the body and having a lip extending within the slot to prevent rotation of the same, a handle secured upon the outer end of the stem, and a spring within the barrel normally holding the same in outer inactive position.

2. A dispensing device including a casing having a lower sieve-like discharge portion and an upper open end, a hollow barrel rotatably mounted through the casing, a non-rotatable stem movable within the barrel, said stem and said barrel having relatively engaging threads to cause rotation of the barrel upon longitudinal movement of the stem, and a stirring frame mounted on and rotatable with the barrel within the casing and having a cover plate normally covering the lower discharge portion of the casing.

3. A dispensing device comprising a hollow casing having an upper open end and a series of lower discharge openings, and pro-

vided with a horizontally projecting stem, a barrel rotatably mounted through the casing and within said stem, a non-rotatable spring controlled stem having an outer handle and telescoping within the barrel at one end, said stem and said barrel having relatively engaging threads to cause rotation of the latter upon longitudinal movement of the former, a stirring frame within the casing and secured upon said barrel, said stem of said casing having a threaded counter-bore at its free end and a supporting bracket having a threaded stud engaged within the threaded counter-bore, for the purpose described.

4. A dispensing device comprising a hollow casing having an upper open end and a series of lower discharge openings and provided with a horizontally projecting stem, a barrel rotatably mounted through the casing and within said stem, a non-rotatable spring controlled stem having an outer handle and telescoping within the barrel at one end, said stem and said barrel having relatively engaging threads to cause rotation of the latter upon longitudinal movement of the former, a stirring frame within the casing and secured upon said barrel, apertured stirring arms carried by said frame, and a cover plate also covered by the frame and normally covering the discharge openings of the casing for the purpose described.

5. A dispensing device including a rotatable agitator, a rotatable barrel on which the agitator is mounted open at its opposite ends, a hollow stem telescoping within the barrel at one end, said stem and said barrel having relatively engaging threads, means to prevent rotation of the same, a handle secured upon and closing the outer end of the stem, a plug closing the relatively opposite end of the barrel and having a rod projecting axially through the barrel and into the hollow of the stem, and a spring coiled around the said rod between the plug and the closed outer end of the stem, for the purpose described.
